UNITED STATES PATENT OFFICE.

ELMER N. DOWNES, OF CHARLOTTE, NORTH CAROLINA, ASSIGNOR TO J. & D. TIRE COMPANY, OF CHARLOTTE, NORTH CAROLINA, A CORPORATION OF DELAWARE.

DESIGN FOR A NON-SKID TIRE.

53,006.

Specification for Design.

Patented Feb. 18, 1919.

Application filed September 21, 1918. Serial No. 255,191. Term of patent 14 years.

To all whom it may concern:

Be it known that I, ELMER N. DOWNES, a citizen of the United States, residing at Charlotte, in the county of Mecklenburg and State of North Carolina, have invented a new, original, and ornamental Design for a Non-Skid Tire, as shown in the accompanying drawing, forming part of this specification.

In said drawing Figure 1 is an exterior face or edge view of part of the tire showing the peculiar bas relief ornamental configuration thereof. Figs. 2 and 3 are transverse sectional views of Fig. 1.

The design consists of a central stem like portion A extending longitudinally of the tread, and having equidistant approximately diamond shaped enlargements D; adjacent

each diamond portion D and on opposite sides thereof are approximately oval shaped portions C connected to the diamond portions by stems; and intermediate each pair of oval shaped portions C and closely adjacent and on opposite sides of the stem A are approximately trefoil shaped members B, B. The parts B, C, D are arranged in approximately quincunx order and all parts of the design project above the surface of the body of the tread.

I claim:

The ornamental design for a non-skid tire as shown and described.

ELMER N. DOWNES.

Witnesses:

JOSEPH Q. TAYLOR,
HARRY O. LASHER.
